UNITED STATES PATENT OFFICE.

ROBERT W. PAIN, OF NEW YORK, N. Y., ASSIGNOR TO AEOLIAN COMPANY, OF NEW YORK, N. Y.,
A CORPORATION OF CONNECTICUT.

PUMPING-BELLOWS.

No. 911,065.

Specification of Letters Patent.

Patented Feb. 2, 1909.

Application filed April 20, 1908. Serial No. 498,073.

To all whom it may concern:

Be it known that I, ROBERT W. PAIN, a citizen of the United States, residing at the city of New York, borough of Manhattan, county and State of New York, have invented certain new and useful Improvements in Pumping-Bellows, of which the following is a specification.

This invention relates to improvements in pumping bellows such for example as are used in pneumatic musical instruments or player attachments for musical instruments.

The object of my invention is to provide a new and improved pumping bellows which is simple in construction, and easily and quickly adjusted for different capacities of wind; according to the requirements of the instrument.

In the accompanying drawings, in which like letters of reference indicate like parts in all the figures:—Figure 1 is a side view of my improved pumping bellows and the motor, parts of the bellows being broken away and others shown in section. Fig. 2 is an end view of the bellows, parts being broken away and others shown in section.

I have here shown the bellows as double bellows that is two pairs of bellows, and one bellows of each pair on each side of a central frame constituting a suction chamber 1. On the top of this frame standards 2 are secured in which a crank shaft 3 is mounted which has two cranks 4. By means of a belt pulley 6 on the end of this crank shaft and a belt 7 the crank shaft can be rotated from a motor 8, an electric motor being shown in the drawings. Two bellows 9 are mounted on each side of the suction chamber 1 and each bellows is provided at the swinging end of its movable board with an upwardly projecting arm 10, the arms 10 of two opposite bellows being connected by connecting rods 11 with a crank 4 of the shaft 3, so that when one bellows of two opposite bellows constituting one pair, is expanded, the other bellows of this pair is compressed. Each bellows is provided in its movable board with a series of ports 12 which can be closed by a flexible valve 13 as is customary in bellows. The fixed board in each bellows is provided with a row of ports 14 leading to the wind chest which ports can be closed by a flexible flap valve 15 which is adapted to open into the bellows. The wind chest is divided by a transverse partition 16 into two compart-

ments 17 and 18 and this partition is provided with a series of ports 19 which can be closed by a flexible or flap valve 5 which opens toward the compartment 17 and from the compartment 18. The bottom of the compartment 17 is provided with a series of ports 20 which can be closed by a sliding valve 21 having a series of ports 22 that can register with the ports 20. This valve can be shifted or adjusted by means of a connecting rod 23 so that the player can at will open or close the ports 20. A suction pipe 24 is connected with the compartment 18 of the suction chamber and this pipe 24 is to be connected with the mechanism or suction chambers from which the air is to be exhausted.

The operation is as follows:—When a bellows is collapsed the air is forced out through the ports 12 and when a bellows is expanded it draws air from the suction chamber 1 through the ports 14. When the valve 21 closes the ports 20 both pairs of bellows are effective and the bellows of the compartment 18 exhaust the air entering this compartment through the pipe 24 and the bellows of the compartment 17 exhaust some of the air from the compartment 18 through the ports 19. Whenever, for reasons less air is to be exhausted, for example when less power is required, the bellows of the compartment 17 are thrown out of action by opening the ports 20 of the compartment 17 by means of the slide valve 21 as thereby the compartment 17 is connected direct with the atmosphere and atmospheric air is merely drawn into the bellows of the compartment 17 and forced out again but no air whatever is drawn by the bellows of the compartment 17 from the compartment 18 as the pressure of the air in the compartment 17 is always greater than the pressure of the air in the compartment 18 and the flap valve 5 keeps the ports 19 closed. The operator is thus enabled at any time to readily control the bellows and to vary the suction power of the same.

Having described my invention what I claim as new and desire to secure by Letters Patent is:—

1: In a pumping bellows, the combination with two chambers having valved ports establishing communication between the chambers, of valved pumping bellows in communication with each chamber, means

105

110

for connecting one chamber with the atmosphere at will and means for operating the bellows, substantially as set forth.

2. In a pumping bellows, the combination with two chambers having valved ports establishing communication between the chambers, of valved pumping bellows in communication with each chamber, a suction pipe connected with one chamber, and 10 means for connecting the other chamber with the atmosphere at will, and means for operating the bellows, substantially as set forth.

3. In a pumping bellows, the combination with two chambers, of a valve controlling communication between the two chambers, and opening toward one chamber, a suction pipe connected with the chamber from which the above mentioned valve 15 opens, means for connecting the chamber into which the valve opens at will with the 20

atmosphere, valved pumping bellows in communication with each chamber and means for operating the bellows, substantially as set forth.

4. In a pumping bellows, the combination with two chambers, of valved ports establishing communication between the two chambers, pumping bellows, means for operating the bellows, a suction pipe connected with one chamber, the other chamber having ports leading to the atmosphere and a valve for opening and closing said ports, at will, substantially as set forth.

In testimony whereof, I have signed my name to this specification in the presence of two subscribing witnesses, this 17th day of April 1908.

ROBERT W. PAIN.
